UNITED STATES PATENT OFFICE

143,602

DESIGN FOR A COMBINED FIGURED CIGARETTE CONTAINER AND MUSIC BOX

William T. Korn, New York, N. Y.

Application September 24, 1945, Serial No. 122,283

Term of patent 7 years

(CL. D85—2)

To all whom it may concern:

Be it known that I, William T. Korn, a citizen of the United States of America, residing in New York city, county of New York, and State of New York, have invented a new, original, and ornamental Design for a Combined Figured Cigarette Container and Music Box, of which the following is a specification, reference being had to the accompanying drawings, forming part thereof, wherein

Figure 1 is a front elevational view of a combined figured cigarette container and music box showing my new design.

Figure 2 is a top plan view of the combined

figured cigarette container and music box shown in Figure 1, drawn on a smaller scale showing the design in open position.

Figure 3 is an end elevational view of the combined figured cigarette container shown in Figure 1, drawn on a smaller scale.

The rear of the combined figured cigarette container and music box is substantially plain in appearance.

I claim:

The ornamental design for a combined figured cigarette container and music box, substantially as shown and described.

WILLIAM T. KORN.
